UNITED STATES PATENT OFFICE.

JOHN L. CHENEY, OF LOWELL, MASSACHUSETTS.

SPOOL AND BOBBIN.

SPECIFICATION forming part of Letters Patent No. 290,534, dated December 18, 1883.

Application filed March 21, 1883. (No model.)

To all whom it may concern:

Be it known that I, JOHN L. CHENEY, a citizen of the United States, residing at Lowell, in the county of Middlesex and Commonwealth of Massachusetts, have invented certain new and useful Improvements in Spools and Bobbins, of which the following is a specification.

My invention relates to spools and bobbins formed of wood and having a barrel circular in cross-section, and circular heads secured to the end of the barrel; and it has for its object to connect the heads to the barrels in a cheap and effectual manner.

15 In the accompanying drawings, Figure 1 is an oblique view of a spool constructed according to my invention, the lower end being in section; Fig. 2, an end view of the same; Figs. 3 and 4, central longitudinal sections of the head and barrel, respectively; Fig. 5, an oblique view of the ring-key.

The common practice is to provide the central opening of the head with a female screw and to cut a corresponding thread on the end of the bobbin, and to screw the head onto the barrel against a shoulder. In this case the threads of the barrel are likely to be broken by screwing the head with too much force against the shoulder. Heads are also secured 25 by pins, which shrink and come out, and are sometimes held on by tapering bushings driven into the reduced ends of the barrels to expand them and fill the opening in the head, such opening being sometimes of uniform diameter

30 and sometimes flaring. Such bushings frequently shrink and fall out, and the reduced end of the spool is necessarily made thinner or split, and thereby weakened, to allow it to spread. I form a shoulder, D, on the barrel

40 A in the usual manner; but I make the barrel from the shoulder to the nearest end of the barrel like a frustum of a cone, E. I provide the head B with a flaring opening, F, the smallest diameter of said opening being on the

45 inside of the head, and preferably just large enough to admit the end of the barrel, and

place the head around the reduced end E of the barrel and against the shoulder in the usual manner. I then make an annular wedge or ring key, C, of the shape and size of the 50 space between the end of the barrel and the sides of the opening in the head when the head is on the end of the barrel and concentric with the barrel, this space being wider at the end of the barrel than at the shoulder, as the opening in the head is more flaring than the reduced end of the barrel. This ring-key is therefore an annular wedge, and is made of wood, the grain running from the thick to the thin edge of the key C. The ring is intended 55 to be just large enough to wholly fill the space between the barrel and the head, and is sawed or split through at C' on one side, that it may be expanded to take in the end of the barrel. Glue may be applied to the key by dipping 60 the thin end of it in glue for about half its length, and it is then placed in the space and driven firmly in between the reduced end of the barrel and the head, the key closing about the barrel and filling the entire space between 65 the said barrel and head.

It will be seen that the ring-key will remain in place, and will serve to secure the head of the barrel until it becomes wholly detached from both the head and the barrel, and that 70 these two parts cannot be separated while the key remains in place. A wedge of pliable metal might be used in place of a wooden wedge.

I claim as my invention—

The combination of the barrel provided with a shoulder and the end flaring outward from said shoulder, the head having a central outwardly-flaring opening, and an annular wedge adapted to fill the space between said head 75 and the reduced end of said barrel, as and for the purpose specified.

JOHN L. CHENEY.
